ARTICULATED JOURNAL BOX LID

Donald D. Bryant, Huntington, W. Va.

Application October 13, 1947, Serial No. 779,608

20 Claims. (Cl. 308—47)

1

This invention is a novel articulated lock-seal lid adapted to be fitted to journal boxes of standard freight car, passenger car, electric car or rolling stock, which boxes contain a journal brass, packing and oil, the journal box being mounted upon a wheeled axle. The present invention is an improvement upon the lock-seal lid shown in my co-pending application, Serial No. 688,723, filed August 6, 1946, now Patent No. 2,498,245 dated February 21, 1950.

The principal object of the invention is to provide an articulated journal box lid embodying certain novel features of construction herein-after set forth.

I will explain the invention with reference to the accompanying drawings, which illustrate several practical embodiments thereof, to enable others familiar with the art to adopt and use the same; and will summarize in the claims the novel features of construction, and novel combinations of parts, for which protection is desired.

In said drawings:

Figure 1 is a vertical section on the line 1—1 Fig. 2 through the outer end of a journal box, showing my novel articulated lid applied thereto and showing the lid in closed position.

Fig. 2 is a front elevation of the parts shown in Fig. 1.

Fig. 3 is a view similar to Fig. 1 but showing the lid open.

Fig. 4 is a side elevation of the projection lock detached.

Fig. 5 is a front elevation of the projection lock, shown in Fig. 4.

Fig. 6 is a front elevation similar to Fig. 2 but showing a modification of the articulated lock-seal lid.

Fig. 7 is a vertical section on the line 7—7, Fig. 6.

The drawings show my novel articulated lock-seal lid applied to a journal box for illustrative purposes only.

As shown in Fig. 1, the standard journal box J has a rough-cast open outer end, over which opening my novel articulated lid is hingedly mounted, the opening being usually formed during the casting operation and left unfinished. Journal box J is provided with a standard hinge-lug J1 on its top above the open end, said hinge-lug J1 being provided with a bore J2 for a pintle pin 2 for the lid, the top face of lug J1 sloping inwardly and downwardly substantially normal to the open outer end of the journal box, as indicated as J3 (Figs. 1 and 3), while the front face

2

J4 of lug J1 slopes substantially vertically, as shown in Figs. 1 and 3. The above lug J1 is standard construction as nearly all journal boxes have lugs formed in the above manner, and hence 5 the journal box J forms no part of my present invention.

Hingedly mounted upon the pintle pin 2 of the lug J1 is a Y-shaped member 1, adapted to overlie the opening at the outer end of journal box J, 10 said Y-shaped member 1 consisting of a resilient strip 1a disposed centrally of the opening of the journal box lid, the same having a T-shaped head 1b disposed at approximately the center of the opening of the journal box J, and having upwardly extending legs 1c at the ends of the head 1b, which legs 1c terminate at their upper ends in outwardly and downwardly extending loops 1d, which loops terminate in cylindrical eyes 1e through which the pintle pin 2 extends, the eyes 20 1e being disposed at opposite sides of the lug J1. By the above construction, the Y-shaped member 1 is hingedly mounted upon the pintle pin 2, the loops 1d resiliently urging the Y-shaped member 1 toward the opening of the journal box J when 25 in the position shown in Figs. 1 and 2.

In order to maintain the Y-shaped member in the position shown in Figs. 1 and 2, the lower end of the member 1a has a return bend 1f terminating in an eye 1g, the outer end of which extends downwardly as at 1h to form a hand-grip for unlocking the Y-shaped member 1. Upon the outer face of journal box J, below the opening therein, is an L-shaped projection lock 3 (Figs. 1, 3, 4 and 5) preferably welded thereto or cast 30 thereon, said projection having a downwardly extending lip 3a adapted to overlie the eye 1g when the Y-shaped member 1 is in the position shown in Figs. 1 and 2, a roller 4 being journaled in the eye 1g of Y-shaped member 1 so as to readily engage and disengage, from below, the lip 3a of projection lock 3. By the above construction, when 35 the Y-shaped member 1 is in the position shown in Figs. 1 and 2, the roller 4 will underlie the lip 3a and will maintain the Y-shaped member 1 yieldably across the opening of the journal box J, assisted by the resiliency of the loops 1d at the upper end of the legs 1c of the Y-shaped member 1. When, however, the handle 1h is pulled outwardly (to the right, Fig. 1), the resiliency of the 40 member 1a will permit the roller 4 to roll under the lower end of lip 3a and thereby unlock the Y-shaped member 1 from its normal closed position, so that the member 1 may be swung upwardly into the position shown in Fig. 3, wherein same 45 is disposed at an angle of substantially 90° to the

open end of the journal box to permit ready packing or servicing of the journal box J.

Mounted in an articulated manner upon the Y-shaped member 1 is a separate lid member 5 of shape corresponding with that of the opening of journal box J, the same being preferably of somewhat larger area than said opening and having inturned peripheral flanges 5a. On the underside of lid 5 is a gasket retainer frame 6 of substantially the same shape as the lid 5 but of smaller size, frame 6 being preferably welded as is 6a to the lid 5. Frame 6 is provided with an out-turned lip, as shown, extending towards the flanges 5a, and a replaceable gasket 7 of a yieldable oil-resistant rubber-like material or other oil-resisting and pliable, yieldable material of shape corresponding to that of frame 6 is stretched over the frame 6 and positioned between the flanges 5a of lid 5 and the flanges of frame 6, as shown in Figs. 1 and 3. The gasket 7 is thus so disposed on the lid 5 that same will squarely contact the walls of the journal box J around the opening therein, as clearly shown in Fig. 1 to effect an oil-tight seal notwithstanding the rough finish of the box J around the opening. Gasket 7 is retained by the flanges 5a and the flange of frame 6 so that it will remain in place when the lid is raised, but gasket 7 is readily changeable or replaceable when the lid is open without removing the lid from the journal box J.

In order to secure lid 5 to the Y-shaped member 1, a connecting plate 8 is provided, substantially of rectangular shape, plate 8 overlying the T-shaped head 1b and the upper end of member 1a of the Y-shaped member 1, said plate 8 having its four corners depressed as at 8a, rivets 9 passing through the depressed corners 8a and through the lid 5, as shown more particularly in Fig. 2. By the above construction, the central portions of the plate 8 are spaced from the lid 5 sufficiently to permit the upper end of leg 1a and the T-shaped head 1b of Y-shaped member 1 to loosely fit between the plate 8 and the lid 5, so that the lid 5 is susceptible of appreciable lateral, longitudinal, and angular movement with respect to the Y-shaped member 1, limited by the clearance between the central portion of plate 8 and lid 5, thus permitting the lid 5 to articulate with respect to the Y-shaped member 1.

The upper end of plate 8 is offset outwardly to form a hood 8b, and its upper end extends between the legs 1c of Y-shaped member 1, but is spaced therefrom; and in the closed position of lid 5 (Fig. 1) the upper end of same slightly overlaps the upper face J3 of the hinge-lug J1 but is spaced above said upper face J3. Below the hood portion 8b of plate 8 is a flat spring 10, having a reverse bend 10a at its lower end secured by rivets 11 or the like to the outer face of lid 5, said spring 10 having its upper outer end rounded as at 10b and lying opposite but slightly spaced from the outer vertical face J4 of hinge-lug J1 when the lid 5 is in closed position shown in Fig. 1. When however lid 5 is raised into position shown in Fig. 3, the rounded upper end 10b will ride over the upper end of outer face J4 of hinge-lug J1 and will yieldably contact the upper face J3 of hinge-lug J1, as shown in Fig. 3, the spring 10 being flexed upwardly in such position so that the spring 10, having its outer end flexed and seating upon the upper face J3 of hinge-lug J1 will hold the lid 5 in its raised position shown in Fig. 3, thereby eliminating the necessity of the serviceman from having to hold the lid 5 open in order

to grease and check the condition of the journal box J.

In order to pivot the lid 5 on the Y-shaped member 1 the lid 5, at approximately its central point, is provided with an offset or raised button 5x, which underlies the T-shaped head 1b of Y-shaped member 1, as shown in Figs. 1 and 2, said button 5x constantly contacting the underside of said T-shaped base 1b and serving as a pivot point so that the articulated lid 5 may assume different positions having a slight angularity with respect to the plane of the Y-shaped member 1. Thus the articulated lid 5 has a central button or bearing point 5x; also the Y-shaped member 1 extends over this central button 5x and crosses the lid 5 itself, and forms the handle for raising or locking closed the lid 5. When the lid 5 is closed the loops 1d of hinges 1e at the top of the Y-shaped member 1 force the lid 5 shut, and the handle 1h locks it by means of roller 4 at the front, this action permitting the middle section of the Y-shaped member 1 to rest on the center button 5x formed or pressed outwardly in the lid 5, and thus permits the lid 5 to articulate under car movement; also to articulate in event the open face of the journal box becomes worn, or is not cast true or square with the pintle pin hole J2 of lug J1; also to articulate in event the lug J1 is not cast true or square with respect to the end face of journal box J; or to articulate by reason of other casting irregularities which would prevent the lid 5 from properly seating itself. To overcome these slight casting flaws or faults, articulation of the lid 5 is desirable. Should a casting face be slightly out of square or true, the lid 5 by articulation, i. e. tilting slightly about its central point, will seat itself to the irregular face to effectively seal the journal box opening.

Air holes 5h may be drilled or punched in this lid 5 as desired by the purchaser, the holes being drilled or punched through the lid 5 proper and covered by the hood 8b which acts as a cover or shield for the air holes to prevent dirt or moisture from entering the journal box J, yet allowing air to circulate from the journal box under the hood 8b to the atmosphere. The hood interior may be filled with hair or fiber to act as a dust filter if desired.

A round steel ball may be fitted or otherwise seated into the raised center button 5x of the lid, so that the projecting portion of the steel ball may contact the T-shaped base 1b of the Y-shaped member 1 facilitating articulation.

In the construction shown in Figs. 6 and 7, the Y-shaped locking member 1 is shown as applied to the lock-seal lid shown in my co-pending application Serial No. 683,723, filed August 6, 1946, similar parts being similarly numbered. In this modification, the lid or cover 5 is articulated with respect to the Y-shaped locking member 1 which latter is hingedly mounted as at 1d, 1e to pintle pin 2, as in the preceding figures, the articulating means consisting of the plate 8 which loosely embraces the base 1b of the Y-shaped member 1 and is secured thereto by the rivets 9 as in the preceding figures. However, the gasket securing frame 6 is omitted, but the lid or cover 5 is provided with the peripheral flanges 5a, and the lid or cover 5 carries the spring 10 riveted thereto as in the preceding figures.

In this modification, a frame 20 (Fig. 7) of shape corresponding with the opening in the end of journal box J is provided across the open end thereof, the same carrying on its inner face a gasket 21 secured thereon in any desired manner and contacting the end of the journal box around

the opening, as in my co-pending application Serial No. 688,723. The frame 20 carries on its outer face a gasket 22 (Fig. 7) extending beyond the outer face thereof, gasket 22 being engaged directly by the inner face of the cover or lid 5 when the lid is closed, as shown in Fig. 7. Frame 20 is provided at its upper end with eyes 20a (Fig. 6) which are disposed between the hood 8b and the eyes 1e of Y-shaped member 1, as clearly shown in Fig. 6, the eyes receiving the pintle pin 2 and being connected with the frame 20 by means of strips 20b which are resilient so as to maintain the upper portion of frame 20 in firm contact with the end of the journal box around the opening therein.

At the lower end of frame 20 is a resilient tongue 20c which enters the opening in the journal box and has its outer end 20d engaged with the inside of the journal box so as to resiliently hold the lower end of frame 20 in firm contact with the open end of the journal box around the opening therein. By the above construction, the frame 20 will be maintained in firm contact with the journal box, and the gasket 22 will effectively seal the joint between frame 20 and the journal box at all times. When the lid or cover 5 is in closed position, shown in Fig. 7, the gasket 22 will form a seal between the frame 20 and the cover 5.

In this modification, the projecting lug 3 shown in Figs. 3, 4, and 5 is omitted. However, the leg 1a of Y-shaped member 1 is formed in the same manner shown in the preceding figures, the same having the return bend 1f and the handle portion 1h with the roller 4 journaled therein, but roller 4 is adapted to normally engage the rear face of frame 20 from the underside of said frame, as shown in Fig. 7, when the Y-shaped member 1 is in closed position shown in Fig. 7. When, however, the handle 1h is pulled to the right (Fig. 7) 40 the roller 4 will ride under the lower end of frame 20, thereby releasing the Y-shaped member 1 from its normal locked position, permitting the Y-shaped member and the cover 5, which is articulated thereto, to be raised into raised position, while the frame 20 will remain in the position shown in Fig. 7 in which position the frame 20 will not obstruct proper servicing of the journal box when the cover 5 is raised.

I do not limit my invention to the exact form shown in the drawings, for obviously changes may be made therein within the scope of the claims.

I claim:

1. An articulated lock-seal lid for journal boxes or the like having an end opening and having a hinge lug on its top above said opening carrying a horizontally disposed pintle pin, comprising a resilient member having resilient loops at the upper ends of its upper legs terminating in eyes engaging the pintle pin at opposite sides of the lug, said loops resiliently urging the upper end of the member towards the opening of the journal box; said member being adapted in one position to overlie said opening; means on the lower end of the member for maintaining the member positioned across the opening; a cover plate mounted on the said member for articulated movement with respect thereto and adapted in one position to close said opening; and means on the plate adapted to engage the top of the hinge lug when the plate and member are swung upwardly to hold same in such position.

2. In a lid as set forth in claim 1, said member being Y-shaped.

3. In a lid as set forth in claim 1, a locking lug on said journal box below the opening having a downwardly extending lip; said lower leg of the member having a return bend terminating in an eye underlying the lip and adapted to contact the rear face of the lip when the lid is closed, said lip and eye forming said maintaining means; and said lower leg continuing downwardly below said eye.
4. In a lid as set forth in claim 1, a locking lug on said journal box below the opening having a downwardly extending lip; said lower leg of the member having a return bend terminating in an eye underlying the lip, said member continuing downwardly below said eye; and a roller journaled in the eye adapted to contact the rear face of the lip when the lid is closed; said lip and roller forming said maintaining means.
5. In a lid as set forth in claim 1, an open frame across said opening having eyes at its upper end engaged by said pintle pin, and having a tongue at its lower end entering the opening and resiliently engaging the inner wall of the journal box; the lower leg of the member having a return bend terminating in an eye underlying the lower end of the frame and adapted to contact the rear face thereof when the member is swung downwardly across the opening; said eye forming said maintaining means; and said lower leg continuing downwardly below said eye.
6. In a lid as set forth in claim 1, said plate being disposed at the inner face of the member; a connecting plate having its central portion offset outwardly to loosely cover the central portion of the member, said connecting plate being secured at its corners to the first plate; and said first plate having an outwardly extending button normally contacting the central portion of the member and forming the pivot point thereof.
7. In a lid as set forth in claim 6, said connecting plate having an outwardly offset hood portion extending from its upper edge curved to overlie the hinge lug; and said holding means comprising a flat steel spring secured to the first plate at its inner end beneath the hood and having its outer end adapted to engage the hinge lug only when the lid is open.
8. In a lid as set forth in claim 7, a breather hole in the first plate below the hood of the connecting plate.
9. An articulated lock-seal lid for journal boxes or the like having an end opening and having a hinge lug on its top above said opening carrying a horizontally disposed pintle pin, comprising a resilient member having resilient loops at the upper ends of its upper legs terminating in eyes engaging the pintle pin at opposite sides of the lug, said loops resiliently urging the upper end of the member towards the opening of the journal box; said member being adapted in one position to overlie said opening; means on the lower end of the member for maintaining the member positioned across the opening; a cover plate mounted on the said member for articulated movement with respect thereto and adapted in one position to close said opening; and means on the plate adapted to engage the top of the hinge lug when the plate and member are swung upwardly to hold same in such position, said plate having resilient eyes at its upper end engaged by the pintle pin and disposed at opposite sides of the hinge lug.
10. An articulated lock-seal lid for journal boxes or the like having an end opening and having a hinge lug on its top above said opening

carrying a horizontally disposed pintle pin, said lug having a substantially horizontal top face, said lid comprising a resilient member having resilient loops at the upper ends of its upper legs terminating in eyes engaging the pintle pin at opposite sides of the lug; said loops resiliently urging the upper end of the member towards the opening of the journal box; said member being adapted in one position to overlie the said opening; means on the lower end of the member for yieldably maintaining the member positioned across the opening; a cover plate mounted on the said member for articulated movement with respect thereto and adapted in one position to close said opening; and means on the plate adapted to yieldably engage the top face of the hinge lug when the plate and member are swung upwardly to hold the plate and member in such position.

11. In a lid as set forth in claim 10, said member being Y-shaped.

12. In a lid as set forth in claim 10, a locking lug on said journal box below the opening having a downwardly extending lip; said lower leg of the member having a return bend terminating in an eye underlying the lip adapted to contact the rear face of the lip when the lid is closed, said lip and eye forming said maintaining means and said lower leg continuing downwardly below said eye.

13. In a lid as set forth in claim 10, a locking lug on said journal box below the opening having a downwardly extending lip; said lower leg of the member having a return bend terminating in an eye underlying the lip, said member continuing downwardly below said eye; and a roller journaled in the eye adapted to contact the rear face of the lip when the lid is closed, said lip and roller forming said maintaining means.

14. In a lid as set forth in claim 10, an open frame across said opening having eyes at its upper end engaged by said pintle pin, and having a tongue at its lower end entering the opening and resiliently engaging the inner wall of the journal box; the lower leg of the member having a return bend terminating in an eye underlying the lower end of the frame and adapted to contact the rear face thereof when the member is swung downwardly across the opening; said eye forming said maintaining means; and said lower leg continuing downwardly below said eye.

15. In a lid as set forth in claim 10, said plate being disposed at the inner face of the member; a connecting plate having its central portion offset outwardly to loosely cover the central portion of the member, said connecting plate being secured at its corners to the first plate; and said first plate having an outwardly extending button normally contacting the central portion of

the member and forming the pivot point thereof.

16. In a lid as set forth in claim 15, said connecting plate having an outwardly offset hood portion extending from its upper edge curved to overlie the hinge lug; and said holding means comprising a flat steel spring secured to the first plate at its inner end beneath the hood and having its outer end adapted to engage the hinge lug only when the lid is open.

17. An articulated lock-seal lid for journal boxes or the like having an end opening and having a hinge lug on its top above said opening carrying a horizontally disposed pintle pin comprising a Y-shaped resilient member having resilient loops at the upper ends of its upper legs terminating in eyes engaging the pintle pin at opposite sides of the lug and adapted in one position to overlie the said opening; means on the lower end of the member for yieldably maintaining the member positioned across the opening; and a plate mounted on the said member for articulated movement with respect thereto and adapted in one position to close said opening.

18. In a lid as set forth in claim 17, said plate being disposed at the inner face of the member; a connecting plate having its central portion offset outwardly to loosely cover the central portion of the member, said connecting plate being secured at its corners to the first plate; and said first plate having an outwardly extending button normally contacting the central portion of the member and forming the pivot point thereof.

19. In a lid as set forth in claim 18, said connecting plate having an outwardly offset hood portion extending from its upper edge curved to overlie the hinge lug; and said holding means comprising a flat steel spring secured to the first plate at its inner end beneath the hood and having its outer end adapted to engage the hinge lug only when the lid is open.

20. In a lid as set forth in claim 17, a locking lug on said journal box below the opening and having a downwardly extending lip; said lower leg of the member having a return bend terminating in an eye underlying the lip, said member continuing downwardly below said eye; and a roller journaled in the eye adapted to contact the rear face of the lip when the lid is closed, said lip and roller forming said maintaining means.
